UNITED STATES PATENT OFFICE.

WILLIAM HENRY ILLINGWORTH, OF HALIFAX, ENGLAND.

ELECTRICAL CUT-OUT OR CIRCUIT-BREAKER.

1,392,873.

Specification of Letters Patent.

Patented Oct. 4, 1921.

Application filed July 8, 1920. Serial No. 394,822.

(GRANTED UNDER THE PROVISIONS OF THE ACT OF MARCH 3, 1921, 41 STAT. L., 1313.)

To all whom it may concern:

Be it known that I, WILLIAM HENRY ILLINGWORTH, a subject of the King of Great Britain, residing at 1 Ruskin Terrace, Lee Mount, Halifax, in the county of York, England, have invented certain new and useful Improvements in Electrical Cut-Outs or Circuit-Breakers, (for which I have filed an application in Great Britain, February 18, 1919, Patent No. 138,439,) of which the following is a specification.

This invention relates to an electrical cut-out or circuit breaker of the kind described in my prior U. S. Patent No. 1,316,095, granted September 16, 1919, with the exception that in this case, one or both contacts are situated to one side of the column and communicate therewith through the intervention of one or more branch columns each of which is larger in cross sectional area than the main column. The latter also is reduced in cross sectional area at any predetermined portion of its length for a short distance which may for example be half an inch. This construction insures that the point of highest resistance will always be situated at the reduced portion. The position of the portion of reduced area is varied for different amperages but it is always so placed that the whole of the mercury that is above the reduced portion will be discharged over into the well when the column parts. The upper end of the column is advantageously restricted above the reduced portion to insure that under no circumstance will vaporization take place below the reduced portion. The position of one of these branch columns in relation to an overflow or well determines the sensibility of the apparatus and also whether it is to work by the breaking of the main column or merely by the expansion thereof. When the apparatus is employed on a distribution board or other class of work in which a small current is used it is provided with a pump which is automatically actuated to remake the column by tilting the apparatus.

In the accompanying drawings:—

Figure 1 is a vertical section of an electrical cut-out constructed in accordance with this invention.

Fig. 2 is a plan and Fig. 3 a plan with the top cover removed.

Fig. 4 is a vertical section of a carrier provided with a detachable core. 55

Fig. 5 is a plan of a carrier with four columns arranged in parallel.

Fig. 6 is a section showing a carrier provided with an automatically actuated pump.

Fig. 7 is a section showing a form of 60 horizontal carrier and Fig. 8 shows a pump applied to a horizontal carrier.

Referring to Fig. 1, a carrier A is constructed from porcelain or other appropriate insulating material and has a passage *a* 65 communicating with two branch passages *a*¹ *a*². *a*³ indicates the portion of reduced cross sectional area and the portion *a*⁴ that is above same is shown smaller than the portion of the passage that is below *a*³ for the 70 reason already given. The length of the passage *a* below the restricted portion *a*³ is immaterial and can be regulated to suit any particular requirement. Formed in the top of the carrier at one side of the passage *a* 75 is a well or overflow *a*⁵, in which is fitted a transparent inspection tube or indicator *a*⁶ to show when the mercury in the main column has parted. For this purpose the tube is fitted a little above the bottom of the 80 well above the level of any surplus mercury which remains permanently in the well. The top of the carrier is covered by a cap *a*⁶ or other suitable closure having one or more vent apertures *a*⁷ for the escape of gas 85 produced by vaporization of mercury and the bottom of the passage is closed by a stopper *a*⁸ or other appropriate device. Bolted to the carrier are two metal contacts B B¹. The contact B is pivoted through a bayonet 90 slot connection in a spring contact *b* on an insulating base *b*² and the contact B¹ is slidably mounted in a similar contact *b*¹ on the insulating base, any suitable packing or jointing material being employed for making a fluid tight joint between the carrier and the contacts. The latter are formed with recesses *b*³ to receive a body of mercury and insure a large surface contact at this point. The branch passage *a*¹ advantageously inclines in an upward direction so that it is always full of mercury each time the passage *a* is completely filled. The level or position of such branch passage in relation to the top *a*⁹ of the well or overflow determines the sensibility of any apparatus of a

100
105

given size. For example, if the level is some distance below the top of the overflow it would be necessary to rely upon vaporization of a portion of the main column to 5 break the circuit. If the level is level with or only slightly below the top of the column and point of overflow, expansion of mercury would cause a portion to be precipitated over into the well and immediately, the top 10 of the column falling below the level of the branch passage, the circuit would be broken without breaking the column. This action would of course require less current than would be required to vaporize a portion 15 of the mercury. To utilize the apparatus the passage a is filled with mercury to the top a^9 of the well or overflow and until a little of the mercury overflows into the well. When the circuit is broken by a heavier 20 current than the apparatus is designed for, it can instantly be restored by tilting the carrier.

In the example shown in Fig. 4, the carrier is provided with a detachable core C 25 having a vulcanite or other tube c of electrical insulating material screwed into it, a tight joint between its free end and the carrier being made by asbestos or other packing c^1 . To insure that the branch hole in 30 the core will register with the branch passage in the carrier, the core is provided with a key c^2 to enter a key-way a^{10} in the carrier. To insure tight joints at the ends of the core, packings c^3 are employed which 35 become compressed when the stopper a^8 is screwed tight. In Fig. 5 a number of columns A^1, A^2, A^3, A^4 are arranged in parallel and discharge separately into a well a^5 . In Fig. 6, an automatically actuated 40 pump, comprising a plunger D is mounted in a stuffing box d in the cap a^6 , the said plunger being normally retained at the top end of its stroke by means of a spring d^1 encircling the plunger rod d^2 . When the 45 carrier is tilted a button d^3 on the end of the plunger rod comes into contact with a blade spring d^4 with the result that the plunger is forced in against the action of the spring d^1 to displace the mercury that may lie between such plunger and the column and 50 force it into the latter. When the plunger has been forced to the end of its stroke, the blade spring d^4 yields and prevents injury of parts. When the carrier is in the position 55 shown by the broken lines the plunger is just about to be pushed in by further tilting of the carrier. Fig. 7 shows a horizontal carrier A with a passage a reduced at a^3 and sloping upward a little toward the well 60 or discharge aperture a^5 to insure its being kept full of mercury during use. A lip or ridge a^{11} is also provided to separate the column of mercury from the well or overflow. The branch passage a^1 may be arranged im- 65 mediately, or some distance behind this

ridge and the other branch passage a^2 is arranged at the other end of the passage a . When the column parts, or a sufficient quantity of mercury is discharged over the ridge into the well or overflow the circuit is 70 broken. To remake the circuit the carrier is tilted, thereby causing the mercury to flow back over the ridge into the column. A removable plug or stopper a^{12} is advantageously provided above the well or overflow for filling or replenishing purposes and a window a^{13} is also shown for inspection purposes. This type of cut-out is particularly applicable on systems of distribution for underground feeder or distribution 75 boxes. Fig. 8 shows a pump applied to a horizontal carrier. In this example the well or overflow a^5 is arranged to constitute the cylinder for the pump plunger D . The latter is actuated by a button d^3 on a rod d^2 80 which passes through a stuffing box d in a cap a^6 and the return movement is effected by a spring d^1 which encircles the rod d^2 .

What I claim as my invention and desire to secure by Letters Patent of the United 90 States is:—

1. In an electrical cut-out, actuated by the breaking of a column of mercury, the combination of a carrier containing a main passage for the column of mercury, a metal 95 contact situated at one side of the main passage and communicating therewith through a branch passage, a metal contact communicating with another portion of the main passage, an overflow to receive the mercury thrown by vaporization when the column is broken, and an air vent for the free escape of vapor produced by the breaking of the mercury column.

2. In an electrical cut-out, actuated by 105 the breaking of a column of mercury, the combination of a carrier containing a main passage for the column of mercury, the said passage being restricted for a portion of its length, a metal contact situated at one 110 side of the main passage and communicating therewith through a branch passage that is larger in cross sectional area than the restricted portion of the main passage, a metal contact communicating with another portion 115 of the main passage, an overflow to receive the mercury thrown by vaporization when the column is broken, and an air vent for the free escape of vapor produced by the breaking of the mercury column.

3. In an electrical cut-out, actuated by the breaking of a column of mercury, the combination of a carrier containing a main passage having a restricted portion at some 125 part of its length for the column of mercury, a metal contact situated at one side of the main passage and communicating therewith above the restricted portion through a branch passage, an overflow communicating with the main passage and situ- 130

ated to one side thereof, and a metal contact communicating with another portion of the main passage.

4. In an electrical cut-out, actuated by the breaking of a column of mercury, the combination of a carrier containing a main passage for the column of mercury, an overflow situated at one side of the passage and communicating with the upper end thereof, a branch passage communicating with the main passage below the level of the overflow, a metal contact arranged to make large surface contact with the mercury in the branch passage, a second metal contact arranged to make large surface contact with the mercury, a cover adapted to be attached to the top of the carrier and having a curved deflecting surface to deflect the mercury from the main column to the overflow, and a vent aperture for the free escape of gas.
5. In an electrical cut-out, actuated by the breaking of a column of mercury, the combination of a carrier provided with two contacts having laterally projecting blades, a main passage for the column of mercury communicating with said contacts and leading to one of them through a branch passage, an overflow situated at one side of the main passage above the branch passage and in open communication with the main passage, an air vent arranged in open communication with the overflow, an insulated base provided with two contacts respectively arranged in hinged and sliding connection with the contact blades, and a pump that is automatically actuated by the tilting of the carrier to force mercury into the main passage.
6. In an electrical cut-out, actuated by the breaking of a column of mercury, the combination of a carrier provided with two contacts having laterally projecting blades, a main passage restricted at a portion of its length and communicating with said contacts, the connection between said main passage and contact being through a branch passage, an overflow situated at one side of the main passage above the branch passage and in open communication with the main passage, an air vent arranged in open communication with the overflow, an insulated base provided with two contacts respectively arranged in hinged and sliding connection with the contact blades, and a pump that is automatically actuated by the tilting of the carrier to force mercury into the main passage.

In testimony whereof I affix my signature in the presence of two witnesses.

WILLIAM HENRY ILLINGWORTH.
